Primary Examiner—Nelson C. Holtje*Assistant Examiner*—Martie Thompson*Attorney, Agent, or Firm*—Gary L. Griswold; Walter N. Kirn; William L. Huebsch**[57] CLAIM**

The ornamental design for a tape dispenser, as shown and described.

DESCRIPTION

FIG. 1 is a top, left front isometric view of a tape dispenser showing our new design;

FIG. 2 is a top plan view thereof;

FIG. 3 is a bottom plan view thereof;

FIG. 4 is a left side elevational view thereof, the right side elevational view being the mirror image thereof;

FIG. 5 is a front elevational view thereof; and,

FIG. 6 is a rear elevational view thereof.
